UNITED STATES PATENT OFFICE.

HARLAND G. BACON, OF PLAINVILLE, MASSACHUSETTS, ASSIGNOR TO
LINCOLN, BACON & CO., OF SAME PLACE.

ORNAMENTAL CHAIN.

SPECIFICATION forming part of Letters Patent No. 301,789, dated July 8, 1884.

Application filed May 23, 1884. (No model.)

To all whom it may concern:

Be it known that I, HARLAND G. BACON, of Plainville, in the county of Norfolk and State of Massachusetts, have invented an Improvement in Ornamental Chains, of which the following is a specification.

My invention relates to an improvement in the construction of what are known as "roller-chains;" and it consists in the peculiar and novel manner in which the end units are combined with the connecting-staples and the intervening beads to form the chain.

Figure 1 is a plan view and partial section of the roller-chain. Figs. 2, 3, 4, 5, 6, 7, and 8 are detail views.

In the drawings, A A are the center beads of the chain, which are formed and arranged in the chain in the usual manner. B B are the wire staples which serve to secure the beads A in parallel rows of alternating beads, as shown in Fig. 1.

To form the edge units of the chain I first cut out a blank, a, in the form of a cross, as shown in Fig. 3, and fold the radiating arms of the cross in a die to the form shown in the edge elevation, Fig. 4. I also provide a plain circular disk, b, (shown in perspective in Fig. 5,) and also a cap, c. (Shown in section in Fig. 6.) I then arrange an edge unit upon the staple B, as shown in Fig. 7, by passing the parallel wires of the staple upward in the

opposite notches, d d, of the folded cross a', as shown in the end view, Fig. 8, and within the folded arms of the cross I place the disk b, and over the whole I place the cap c, and turn the edge of the cap c inward, thus securely clasping the folded cross a' and forming a finished head for the staple B. After placing the intervening beads A A A over the staple-wires, I place the folded cross a' between the wires of the staples, the wires occupying the opposite notches, d d, of the cross, and twist the ends of the staples together, as shown in Fig. 1, and over the folded ends of the cross a', I place the cap c and press the same in a suitable die, thus closing the edge of the cap around the base of the folded arms of the cross, and forming a desirable finish for the edge units of the chain.

I claim as my invention—

1. The combination, with the beads A A, united by the staples B B, of the folded crosses a' a' and the caps c c, substantially as described.
2. The combination of the staples B, folded cross a', disk b, and cap c, substantially as described.

HARLAND G. BACON.
